INVENTOR—

George F. Hoeffner.

UNITED STATES PATENT OFFICE.

GEORGE F. HOEFFER, OF CHICAGO, ILLINOIS.

BOTTLE-STOPPER.

SPECIFICATION forming part of Letters Patent No. 251,779, dated January 3, 1882.

Application filed November 21, 1881. (No model.)

To all whom it may concern:

Be it known that I, GEORGE F. HOEFFER, a citizen of the United States, residing at Chicago, in the county of Cook and State of Illinois, have invented a new and useful Improvement in Bottle-Stoppers, (which has not been patented to myself or to others, with my consent or knowledge, in any foreign country;) and I do hereby declare the following to be a clear, full, and exact description thereof, reference being had to the accompanying drawings, forming part of this specification.

Like letters and figures refer to like parts wherever they occur.

15 My invention relates to an improvement in bottle-stoppers for closing bottles of all kinds in a quick and secure manner; and the object of said invention is to obtain such a construction of the stopper that, in combination with a 20 stopper-yoke and its lever, it will effect a double corkage, one upon the mouth and lips and the other within the throat of the bottle; to which end said stopper consists of two (a large and a small) circular centrally-perforated 25 concaved metal plates, and of a cone-shaped hollow rubber bulb having at its top a thick interiorly grooved flange, the upper portion of which is fastened between said plates by means of a screw passing through the perforations 30 of said plates into a concaved wooden button inserted into the cone-shaped cavity of said bulb.

I will now proceed to describe my invention, so that others skilled in the art to which it 35 pertains may apply the same.

In the drawings, Figure I indicates the large concaved circular plate, made of galvanized sheet-iron, and perforated in the center *a*. Fig. II indicates the small concaved circular 40 plate, made of sheet-iron, and perforated in the center *b*. Fig. III indicates the concaved button, made of wood, with a small perforation through the center *c* for the guidance of the screw shown in Fig. IV. Fig. IV indicates the screw, made of galvanized wire, and having a head with an eye, *d*, in which is hung the stopper-yoke *F F* shown in Fig. VII. Fig. V indicates a central section of the cone-shaped hollow bulb *H*, made of rubber or other elastic 45 material, having a thick flange, *M M*, at its top, with an interior groove, *n n*, within said flange, as shown in the drawings. Fig. VI in-

55 dicates the stopper, constructed of the several parts above described. Fig. VII indicates a bottle, *Y*, closed by the stopper *K*, embodying 60 my invention, and in which figure *F F* represents a stopper-yoke pivoted to the free ends of the locking-lever *R*, in the eyes *p p* thereof; and *R* represents a locking-lever pivoted to the bottle, within its length, by springing its 65 eyes *p' p'* upon the pintles *t t* of the neckband *S*, which is tightly wired to the neck of the bottle. Fig. VIII indicates a central vertical section of the stopper, showing all of the parts as they appear together in position in the stop- 70 per.

The stopper is constructed as follows: Insert the wooden button into the cone-shaped cavity of the bulb, and place upon it the small plate with its concaved side resting upon the concaved surface of said button and its edge extending into the groove *n n* of the flange of said bulb. Then place the large plate, with its concaved side down, upon the upper surface of said flange, and, passing the screw through 75 the perforations of said plates, screw the same tightly into said wooden button, thereby fastening the upper portion of said flange firmly between the edge of said small plate and the inside surface of the large plate. 80

The advantages of my invention are that the rubber bulb can never become disconnected from the plates and lost, that the stopper can be increased to any reasonable size by merely increasing the diameter of the button, 85 and that the stopper effects a corkage upon the mouth and lips as well as within the throat of the bottle.

The devices may be operated as follows: To close a bottle, place the stopper upon the mouth 90 of the bottle and push the locking-lever *R* up against the head of the vessel, thus bringing the yoke *F F* into line, and forcing the cone-shaped portion of the stopper tightly into the throat and the flange firmly upon the mouth 95 and over the lips of the bottle.

I do not herein claim the combination, with a bottle-stopper, of a locking-lever pivoted to the bottle within its length, and a stopper-yoke pivoted to the free ends of a locking-lever; 100 but,

Having described my invention, what I claim as new, and desire to secure by Letters Patent, is—

1. The elastic stopper-bulb with an interi-
orly-grooved flange fastened between two cir-
cular centrally-perforated concaved metal
plates by a screw passing through the perfora-
tions of said plates into a wooden concaved
button resting in the cone-shaped cavity of
said bulb, substantially as shown and described.
5 2. The combination of two circular centrally-
perforated concaved metal plates, with the

cone-shaped hollow elastic bulb having an in- 10
teriorly-grooved flange, by the upper portion
of said flange being fastened between said
plates, substantially as before set forth.

GEORGE F. HOEFFER.
